UNITED STATES PATENT OFFICE

109,025

DESIGN FOR A GLASS BUILDING BLOCK

Willard Perkins, Finleyville, Pa.

Application March 16, 1937, Serial No. 68,203

Term of patent 14 years

To all whom it may concern:

Be it known that I, Willard Perkins, a citizen of the United States, residing at Finleyville, in the county of Washington and State of Pennsylvania, have invented a new, original, and ornamental Design for a Glass Building Block of which the following is a specification, reference being had to the accompanying drawing, forming part thereof.

In the drawing Fig. 1 is a face view of a glass building block showing my new design, in which a series of spaced transverse flutings divide the interior surfaces of the blocks into well defined

areas, such areas carrying parabolic curves producing a plurality of regularly spaced drapes lying between and limited by the flutings, Fig. 2 an end view thereof partly broken away, and Fig. 3 a top plan view with a fragmentary corner portion broken away to illustrate the interior configuration that results in the appearance of my new design.

I claim:

The ornamental design for a glass building block, substantially as shown and described.

WILLARD PERKINS.
